Primary Examiner — Richard Edgar*Assistant Examiner* — Jessica Ruth Grable(74) *Attorney, Agent, or Firm* — Oyen Wiggs Green & Mutala LLP(57) **CLAIM**

The ornamental design for a display frame as shown and described.

DESCRIPTION

FIG. 1 is a perspective view of a display frame, showing my new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken lines in FIGS. 1-7 represent portions of the display frame that form no part of the claimed design.

1 Claim, 7 Drawing Sheets(56)
